F. L. SCHLEICHER

MACHINE FOR DESCALING BOILERS

Filed Oct. 4, 1926

UNITED STATES PATENT OFFICE.

FREDERICK L. SCHLEICHER, OF ST. LOUIS, MISSOURI

MACHINE FOR DESCALING BOILERS.

Application filed October 4, 1926. Serial No. 139,542.

This invention relates to machines for descaling boilers, or machines that produce by abrasion a finely divided material that remains in suspension in the feed water that passes through the machine on its way to the boiler. The suspended material reacts with the scale-forming solute in the water to form other substances that have no scale-forming tendencies. Hitherto the suspended material has been formed by abrading the sides of an iron conduit by means of steel or iron balls that are driven therethrough by the current of water in the course of its passage to the boiler. Machines operating on this principle are objectionable on account of the wearing out of the walls of the machine itself and further because jamming of the balls in the conduit is of frequent occurrence.

Accordingly, an object of the present invention is to provide a machine of the class described whose casing is not subject to abrasion and whose wearing parts may be easily replaced at a minimum cost.

Another object is the provision of such a machine that is so organized that it can not jam.

Another object is to provide convenient and exteriorly visible means that will indicate whether or not the mechanism in the interior of the casing is in motion.

Another object is to provide means that will maintain the continual engagement of the abrading and abraded members as the wear proceeds.

Another object is to provide means for regulating the speed of the moving parts.

Another object is to provide a machine of the character described, the continuity of whose moving parts will not be materially interrupted by intermittent back pressure from the boiler in case a reciprocating pump is employed to force the feed water into the boiler.

Other objects and advantages will appear in the course of the following description of a preferred embodiment of the invention.

In the accompanying drawing forming part of this specification, in which like numbers of reference denote like parts wherever they occur,

Figure 1 is a sectional view of the machine taken on an axial plane indicated by the line 1—1 in Figure 2, parts being broken away; and

Figure 2 is a sectional view taken on the irregular line 2—2 in Figure 1, parts being broken away.

The casing 1 of the machine comprises an annular lateral wall 2 and a rear wall 3. The open front of the casing 1 is closed by a removable cover plate 4, secured by means of bolts 5 to the flanges 6, extending laterally outward from the front end of the wall 2. A wall 7, exteriorly convex in cross-section, is formed integral with and encompasses the intermediate portion of wall 2 to enclose an intermediate duct 8, and enlarges laterally outward at one point to form a neck 9, having an outwardly and laterally extending flange 10 on its outer end. A central neck 11 is formed integral with and extends rearwardly from the rear wall 3, and is provided at its outer end with a laterally and outwardly extending flange 12. Necks 9 and 11 are connected to respective flanged ends at an interruption in the feed-water pipe by means of bolts that pass through the holes therefor in the flanges of the pipes and the holes 13 in the flanges 10 and 12, respectively, so that the feed water enters the casing 1 through the neck 9 and is discharged therefrom through the neck 11. Openings 14 in the wall 3 afford communication between the chamber 15 in the casing 1 and the interior of the neck 11.

A pintle 16 projects centrally from the wall 3 into the chamber 15, the reduced portion or neck 17 of the pintle passing through the wall and being screw-threaded at its outer end to receive a nut 18, by means of which it is secured to the wall 3. An abrading cylinder 19 is provided with a central bearing 20 that fits the pintle 16 so that the cylinder 19 may turn freely thereon. Cylinder 19 forms the hub of a water wheel 21, that comprises a rim 22 and a spider 23, preferably cast integral with the rim 22 at the front edge of the latter. Spider 23 is located with relation to the cylinder 19 by a boss 24 that projects from the spider and fits closely into the bearing 20, and the spider is secured to the cylinder by means of screws 25, that pass in unthreaded relation through the spider 23 and screw into tapped holes in the front face of the cylinder 19. Teeth or vanes 26 of any suitable or usual form are formed on the outer face of the rim 22.

Bosses 27 project from the inner side of

the wall 3 between the cylinder 19 and the rim 22, and studs 28 are screwed into the said bosses. The spaced-apart ears 29 of brush holders 30 are journaled on opposite ends of 5 the studs 28 and are connected by webs 31, provided at their forward edges with inwardly projected flanges 32. The heads 33 on the outer ends of the studs 28 maintain the 10 holders 30 against lateral displacement on said studs. Brushes 34 of iron, zinc, or other suitable material that is to be abraded to form the suspended material, are secured to the 15 holders 30 by means of screws 35, passing in unthreaded relation through the brushes and screwing into the flanges 32. The brushes 34 are maintained in engagement with the cylinder 19 by means of springs 36, coiled around the studs 28 and each having one end bearing against the rear edge of the web 31 20 and the other end against a respective pin 37. The pins 37 are screw-threaded on their inner ends and screwed into the inner side of the wall 3. The said pins, also, function as stops to prevent contact and resulting 25 abrasion of the brush holders by the cylinder.

Nozzles 38 are exteriorly screw-threaded to fit interiorly screw-threaded openings 39 in the wall 2, and the nozzles are held in the 30 openings so as to direct jets of water from the duct 8 against the vanes 26 of the wheel 21 so as to cause the latter to rotate. To afford convenient access to the nozzles, interiorly screw-threaded openings 40 are formed in the wall 7, through which openings the 35 nozzles may be passed for removal or replacement. The openings 40 may all be closed by plugs 41 screwed thereinto, or, preferably, at least one of the openings 40, in the present instance two, are closed by a valve box 42, 40 externally screw-threaded to fit the screw-threads of the openings 40. The inner end of sleeve 42 is internally screw-threaded to fit the external screw-threads of needle valve stem 43, and the upper end of sleeve 42 enlarges to stuffing box formation and is screw-threaded internally to receive the externally 45 screw-threaded gland 44; employed to compress the packing 45 therein to seal the joint between the gland 44 and the stem 43 passing therethrough. The outer end of stem 43 may be provided with any suitable handle 46. The inner conical end of each stem 43 is aligned with the nozzle 38 adjacent thereto and 50 may be screwed thereagainst to close the opening in the nozzle. Each valve 43 may be adjusted to increase or decrease the flow of water through its nozzle, and thereby accordingly vary the impact of the water from said nozzle against the wheel 21 without diminishing the impact from the other nozzles, so that 55 the flow of water as a whole through the casing may be varied as determined by the needs of the boiler while the full impact may be had from at least some of the nozzles.

60 The central portion of plate 4 preferably

rises outwardly in sleeve formation 47. The outer end of sleeve 47 is recessed internally to receive a glass disc 48, and is screw-threaded externally to receive the internally screw-threaded annular flange 49 of a ring 50 that overlies the marginal portions of the disc 48 to secure the latter in its recess. The inner end of sleeve 47 preferably extends to the spider 23 to prevent forward displacement of the latter on the stud 16. A central stem 51 is 70 screwed into the outer side of spider 23 and projects into the sleeve 47 in juxtaposition to the glass disc 48, where it enlarges laterally into a disc 52. The outer face of disc 52 may be marked in any suitable manner so its rotation will be easily observed through the glass 75 48; as for instance, it may be divided into two semi-circles of different colors. The said disc 52 and its associated parts constitute exteriorly visible means that will indicate 80 whether or not the wheel 21 is in motion.

The casing and cover plate 4 are preferably formed of cast iron, the rim and spider of the wheel 21 of cast bronze, and the screws and studs preferably of machine steel, although other suitable materials may be employed. The cylinder 19 is preferably the abrader and the brushes 34 are of softer material that may be worn down by the abrasive action of the cylinder. The cylinder is preferably formed of hardened steel, while the brushes may be made of iron, copper, zinc, barium, or other metal or alloys of metal that may be found to be best adapted to the kind of water that is fed to the boiler. It will be observed that the principal wear is on the brushes, and that these are maintained in contact with the cylinder by the springs 36 as the wear proceeds, and when worn out, may be easily replaced. It will, also, be observed that all the parts are 90 maintained in definite spaced relation so that no jamming can occur.

When a reciprocating pump is employed to force the feed water into the boiler, the action is intermittent or pulsating, there being intervals when the back pressure from the boiler tends to reverse the flow of the water in the casing 1. It will be observed, however, that by reason of the outlet 11 being located centrally with relation to the wheel 21, the back pressure will act substantially equal on all sides of the face of the wheel, so that there is no tendency to interrupt its rotation.

Having thus fully described this invention, I hereby reserve the benefit of all changes in form, arrangement, order, or use of parts, as it is evident that many minor changes may be made therein without departing from the spirit of this invention or the scope of the following claims.

I claim:

1. In a machine of the character described, a casing, a water wheel mounted to rotate therein, the said casing being arranged to

- direct water to drive said wheel, and means in said casing and driven by said wheel to produce a finely divided material that remains in suspension in the water and reacts 5 with the scale-forming solute in the water to render the latter inactive.
2. In a machine of the character described, a casing, a water wheel mounted to rotate therein, the said casing being arranged to direct water to drive said wheel, an abrading member, and a member abraded thereby, one of said members being driven by said wheel and the other of said members being supported by said casing against rotation with 10 the wheel-driven member.
3. In a machine of the character described, a casing, a water wheel mounted to rotate therein, the said casing being arranged to direct water to drive said wheel, abrading means borne by said wheel and rotatable therewith, and a brush borne by said casing to ride over said abrading means to be abraded thereby.
4. In a machine of the character described, a casing, means therein for producing finely divided descaling material and embodying a rotatable element, a portion of the wall of said casing being transparent, and means borne by said rotatable element and visible 25 through the said transparent wall portion for indicating a state of motion or of rest of said rotatable element.
5. In a machine of the character described, a casing, a water wheel revolvably mounted therein, a plurality of nozzles adapted to direct jets of water against said wheel to rotate the same, valve means for regulating the jet from at least one of said nozzles, and means operated by said wheel for producing 30 finely divided descaling material.
6. In a machine of the character described, a casing having a wheel chamber; a water wheel revolvably mounted therein; a plurality of nozzles disposed around said wheel 35 and adapted to direct jets of water against said wheel to rotate the same; means operated by said wheel to produce finely divided descaling material; the said casing having a discharge opening leading from the wheel 40 chamber, a conduit supplying the nozzles, and an inlet opening for the conduit.
7. In a machine of the character described, a casing having a wheel chamber; a water wheel revolvably mounted therein; and means 45 operated by said wheel to produce finely divided descaling material; the said casing being arranged to project water against the peripheral portion of said wheel to drive the same and having a discharge opening leading 50 laterally from the wheel chamber at the axis of said wheel.
8. In a machine of the character described, a casing, a pair of members rotatable with relation to one another and one of which is adapted to abrade the other and to be operated by the water passing through said casing, and resilient means for maintaining said members in frictional engagement with one another.
9. In a machine of the character described, a casing, a member mounted to rotate therein by the passage of water through said casing, a second member borne by said casing to ride over said first-mentioned member as the latter rotates, so that one of said members 70 abrades the other, and resilient means for maintaining said members in contact.
10. In a machine of the class described, a casing, a rotary abrading element therein adapted to be operated by the passage of the water through said casing, a brush adapted to be abraded thereby, and a holder for said brush pivoted to said casing and detachably connected to said brush, so that said brush may either be engaged with or disengaged 80 from said abrading element by the pivotal movement of said holder in a proper direction.
11. In a machine of the class described, a casing, a rotary abrading element therein 85 adapted to be operated by the passage of the water through said casing, a brush adapted to be abraded thereby, a holder for said brush detachably connected thereto, so that said brush may be either engaged with or disengaged 90 from said abrading element by the movement of said holder in the proper direction, said holder being spring-tensioned to maintain said brush in contact with said abrading element.
12. In a machine of the character described, a casing, an abrading member adapted to be rotated by the passage of water through said casing, a stationary abraded member borne by said casing and resilient means for maintaining said member in intimate contact with said abrading member.
13. In a machine of the character described, a casing, a rotatable member mounted therein and adapted to be operated by the passage of water through said casing, abrading means fixedly carried by said rotatable member and a stationary abraded member borne by said casing.

In testimony whereof I hereunto affix my signature.

FREDERICK L. SCHLEICHER.
